UNITED STATES PATENT OFFICE.

JESSIE L. COWLES, OF ANTIOCH, FLORIDA.

TIE-HOLDER.

1,175,863.

Specification of Letters Patent. Patented Mar. 14, 1916.

Application filed July 22, 1915. Serial No. 41,321.

To all whom it may concern:

Be it known that I, JESSIE L. COWLES, residing at Antioch, in the county of Hillsboro and State of Florida, have invented a new and Improved Tie-Holder, of which the following is a specification.

This invention, which relates to that class of devices used in connection with turned down collars for holding the collar and tie 10 in the desired position on the neckband of the shirt, more particularly is in the nature of an improved attachment for holding the tie within the collar in place after it has been adjusted.

Another object of my invention is to provide an attachment of the general character stated of a simple and economical construction, which can be used in connection with the standard sizes of collars, and which can 20 be readily applied for use and by which, after "taking off" the collar, the tie can be readily removed from the collar and held in condition for being applied to another collar, as desired.

With other objects in view that will hereinafter appear, my invention embodies the peculiar features of construction and combination of the parts hereinafter explained, specifically pointed out in the appended 30 claims, and illustrated in the accompanying drawing, in which:

Figure 1 is a perspective view of my necktie holder the same being shown as applied to a collar, parts of the collar being broken away to the better show the manner in which the holder is mounted within the collar and the tie connects therewith. Fig. 2 is a perspective view of the holder detached. Fig. 3 is a cross section of the collar 40 with the holder therein, taken on the line 3-3 on Fig. 1. Fig. 4 is a plan view of the holder the manner in which the tie is connected therewith being also indicated. Fig. 5 is a cross section on the line 5-5 of

Fig. 1.

My stay or tie holder comprises a resilient band 1 curved to a collar shape, whose rear or loop end is bent up, as at 10, to form a hook for fitting over the shank of the 50 back collar button *a* when the parts are operatively applied as shown in Fig. 1. From the band 1, rise a number of fingers, and these are arranged in pairs, 2-20, at the

opposite front ends of the band, a single finger 3 at the rear or hook end of the band 55 and a single one 4 at each side of the band intermediate of the rear and front fingers, it being understood that more than one of the intermediate fingers 4 may be used on each side of the band, if desired. The several fingers that rise from the band 1, are riveted or otherwise made fast to the said band and the intermediate ones 4, and the ones 20 are bent to form shouldered portions 40 at their point of connection with 60 the band, the reason for which will presently appear. Each of the outer ends of the band is slit to produce a tongue portion that is bent inwardly to form a spring clip 5 for clipping over the lower edge of the 65 inner fold of the collar to thereby hold the stay inside of and at the bottom of the collar.

6 designates the tie which when applied to the stay as is shown in Fig. 1 is woven 75 over the straight fingers and under the intermediate fingers 4-4 and the end fingers 20-20 and in the loops or seats formed by the shouldered portions of the said fingers 20-20 and 4-4, it being readily apparent by 80 referring to the drawing that when the tie is set on the stay in the manner shown in Fig. 1 it will keep its position on the stay.

In putting on the collar with the stay and tie held therein, as stated, and as shown 85 in Fig. 1, the user buttons up the back of the collar on the back button *A* and then brings the front ends of the collar together and fastens them on the front collar button in the usual manner, and since the tie ends 90 are now loose they may be readily tied, it being understood that while the tie ends can be slid along the several fingers of the stay to bring their ends into the desired relation for tying and after the ends thereof 95 are fastened together the said tie will be firmly held from slipping out of place.

What I claim is:

1. A tie holder for collars comprising a resilient band adapted for being inserted 100 into the folds of a collar, a pair of parallel guide fingers projecting from the front ends of the band whereby to form an open ended guide, other fingers vertically projecting from the band that form guides over which 105 the tie may pass; the said band having the

front ends slit to produce tongues, said tongues being bent to form spring clips for fitting over the lower edge of the inner fold of the collar.

5 2. A tie holder for turn down collars that consists of a resilient band whose ends are transversely slit from the bottom edge and turned up to produce spring clamps, a pair

of finger members projected up between the said ends to form open ended guide slots, 10 other fingers projected from the band to form guides for the tie, the said band having a hook portion for engaging the back collar button.

JESSIE L. COWLES.
